(57) **CLAIM**

We claim the ornamental design for a refrigerator, as shown and described.

DESCRIPTION

FIG. 1 is a front perspective view of a first embodiment of a refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 shown in FIG. 1;

FIG. 9 is an enlarged view of the encircled portion 9 shown in FIG. 1;

FIG. 10 is an enlarged view of the encircled portion 10 shown in FIG. 1;

FIG. 11 is an enlarged view of the encircled portion 11 shown in FIG. 1;

FIG. 12 is an exploded front perspective view in which the upper left-side front panel portion is shown separated from the refrigerator;

FIG. 13 is a front perspective view of a second embodiment of a refrigerator showing our new design;

FIG. 14 is a front view thereof;

FIG. 15 is a rear view thereof;

FIG. 16 is a left-side view thereof;

FIG. 17 is a right-side view thereof;

FIG. 18 is a top view thereof;

FIG. 19 is a bottom view thereof;

FIG. 20 is an enlarged view of the encircled portion 20 shown in FIG. 13;

(Continued)

FIG. 21 is an enlarged view of the encircled portion 21 shown in FIG. 13;

FIG. 22 is an enlarged view of the encircled portion 22 shown in FIG. 13;

FIG. 23 is an enlarged view of the encircled portion 23 shown in FIG. 13; and,

FIG. 24 is an exploded front perspective view in which the upper left-side front panel portion is shown separated from the refrigerator.

The short dash-dash broken lines in the figures depict portions of the refrigerator which form no part of the claimed design.

The dot-dot-dash broken lines encircling portions of the claimed design that are illustrated in enlargements form no part of the claimed design.

The gray tones shown in FIGS. 1 to 12 indicate that the gray portions are the same contrasting color, and do not represent any particular color.

1 Claim, 20 Drawing Sheets
